UNITED STATES PATENT OFFICE.

ALFRED JOHNSON, OF PHILADELPHIA, PENNSYLVANIA.

HYDRANT.

Specification of Letters Patent No. 28,674, dated June 12, 1860.

To all whom it may concern:

Be it known that I, ALFRED JOHNSON, of Philadelphia, in the State of Pennsylvania, have invented a new and Improved Hydrant, 5 or Fire-Plug; and I do hereby declare that the following is a full and exact description thereof, reference being had to the accompanying drawings and to the letters of reference marked thereon.

10 The nature of my invention consists in so arranging a diaphragm between the piston and valve of a hydrant when the whole is arranged as is below set forth, so as to prevent the pressure on the head of water from 15 forcing the water above the piston, and in the general construction of my hydrant to prevent waste, &c.

To enable others skilled in the art to make and use my invention I will proceed to 20 describe its construction and operation.

Figure 1 is a perspective view; Fig. 2, section.

Fitting in a pump barrel A, I have the piston B, moved by the piston rod C, which 25 is to be connected by any suitable means to a lever to be situated near the top of the hydrant, so as to be convenient for use. The piston B, moves in the waste chamber D, which is partly closed by the diaphragm 30 E. This is placed so as to divide the opening F of the outlet G and yet allow the water to pass freely around that part which is in the opening F. In the middle of E is an aperture H, through which projects 35 the upper stem K, of the valve L. M, is another diaphragm, the under side of which is the seat of the valve L, L being pressed upward by the spring N, closes the opening O, in the diaphragm M.

40 P, is the lower stem of the valve L, and is of use to guide the valve to its seat. This stem is also controlled by the guide R, at its lower end.

S, is the inlet; T, coupling screw on S, 45 and V, coupling screw on G; W, cap to pump barrel A, keeping out dirt, and guiding C, perpendicularly; X, middle chamber; Z, lower chamber.

The operation is as follows. The supply pipe is soldered to coupling screw T, and the 50 discharge pipe to the screw V, and the connections made to the valve by screwing up the couplings. By raising the hand lever at top of hydrant, the piston B, is forced down till it strikes K, and forces L down. This 55 opens O, in M, and allows the water from S, to flow through Z, then through O, to X, and thence through lower half of opening F, into G, and thence through the discharge pipe to nozzle of hydrant. While the valve 60 is in this state the upper half of the opening F is closed by the piston B, and the waste chamber D, is empty. As long as B, is down upon the diaphragm E, the water flows uninterruptedly. Z, and X are filled with the 65 water in an active state. To stop the flow of water, the hand lever at the top of the hydrant is pressed down. This raises the piston B, which allows the water to flow around that part of E which divides the 70 opening F, until K, being no longer pressed by B, rises; and the valve L closes O, and stops the supply of water. The lower side of B is now on a line with the upper part of F, and the whole discharge pipe, as well as 75 space between B, and E, is filled with water, which would freeze if allowed to remain there, or would saturate the earth if allowed to leak out (as in the common waste cock) and by making the surrounding earth wet 80 increase the danger of its freezing and consequently the hydrant pipes also. To obviate all this the piston B, is still raised until a sufficient space is created under B, in the waste chamber D, to contain all the 85 water in the discharge pipe. The water is now stopped off, the chambers Z, X, and D are filled with water, the earth around the hydrant remains dry, the discharge pipe is empty, all waste or danger of freezing is 90 prevented, and the object of my invention is accomplished.

It will be perceived that the water usually wasted in other hydrants is now under the piston B. The first operation in drawing 95 water, is to force down this piston, the water

under it must rise in the discharge pipe, and the next moment be forced out at the nozzle by the regular supply coming in behind it. This completes the operation of my invention.

To make this available for a fire plug, all that is required is to enlarge the parts to allow a greater body of water to flow, and raising and lowering the piston by a screw, 10 or any other convenient contrivance.

What I claim and desire to secure by Letters Patent is—

The diaphragm E when arranged in the described connection for the purposes set forth.

ALFRED JOHNSON. [L. S.]
